PROTECTOR FOR PERMANENT WAVE
TREATMENTSPierre Albert and Gustaf Wickstrom,
Evanston, Ill.

Application September 13, 1935, Serial No. 40,440

6 Claims. (Cl. 132—33)

Our invention relates to a protector for permanent waves, for example, the Croquignole permanent wave. One purpose is the provision of a protector which shall be convenient and safe to use, which shall firmly hold the hair and prevent dragging on the scalp or hair roots when the hair is being wound up in the curler and which shall also protect the scalp from heat. Another object is the provision of improved means for increasing the clamping effect upon the hair, near the base of the hair, whereby any pull or drag on the hair roots or scalp is prevented. Another object is the provision of improved means for locking the protector in place 15 against the hair. Another object is the provision of improved means for centering the hair in the protector, in such fashion that the particular lock of hair which passes through the protector is concentrated or gathered at a generally central point, for ease in winding upon the curler. Another object is the provision of improved means 20 for securing the curler in relation to the protector. Other objects will appear from time to time in the course of the specification and claims.

We illustrate our invention more or less diagrammatically in the accompanying drawings, wherein—

Figure 1 is a plan view of the device in open position with parts broken away and parts in 30 section;

Figure 2 is a plan view illustrating the protector in closed position;

Figure 3 is a plan view of the curler;

Figure 4 is a side elevation of the protector 35 with the curler in relative position;

Figure 5 is a section on the line 5—5 of Figure 4;

Figure 6 is an enlarged section on the line 6—6 of Figure 4;

Figure 7 is a partial section taken on the line 1—7 of Figure 1;

Figure 8 is a horizontal section through a variant form;

Figure 9 is a section on the line 9—9 of Figure 8;

Figure 10 is a section on the line 10—10 of Figure 9, showing a curler also in place and a heating element;

Figure 11 is a view of an improved curler;

Figure 12 is a plan view of the curler shown in Figure 11;

Figure 13 is a section on the line 13—13 of Figure 12.

Like parts are indicated by like symbols 55 throughout the specification and drawings.

Referring to the drawings, we illustrate a protector which includes two hinged members, generally indicated as 1, 2, which are hinged as at 3 by any suitable hinge structure of sufficient strength to hold the members 1 and 2 in their 5 normal plane in relation to each other when they are moved into open position. Each of the members 1, 2 includes an upper block or surface 4, 4a, which may be of any suitable metal, for example, aluminum, steel or the like, 10 or any other suitable material. It will be observed that the hinge 3 projects outwardly somewhat and tends to separate the blocks 4 and 4a at one end and any suitable abutment 6 may be employed to space them apart at the other. I employ any suitable clamping means which may include an abutment 7, a link or loop 8, a lever 9 to which said loop is pivoted, an abutment 10 to which said lever is pivoted and a manually operable handle portion 11 associated with said lever. It will be observed that when the hand portion 11 is moved into the locking position and the blocks 4 and 4a are secured together at each 15 end there is still a substantial zone of separation between the intermediate portions thereof. 15

Associated with each of the upper blocks 4, 4a, is a lower block or member 12, 12a preferably of a flexible compressible material, for example rubber or sponge rubber. It will be observed that the layer of rubber projects inwardly somewhat 20 beyond the layer of metal of the blocks 4, 4a, and is provided with a tongue or face upwardly extending into the separating aperture between the two blocks 4, 4a. This provides opposed lips of rubber indicated as at 13, 13a, which are preferably of such thickness that, when the locking means above described is in locking position the opposed edges of the members 4, 4a clamp and compress very strongly the rubber lips 13, 13a, 25 whereby the hair is very firmly gripped between the two, when the protector is clamped about the base of a lock of hair. 30

In order to increase this pressure where necessary I may set into one of the flexible blocks, for example, the block 12a, an abutment or pressure 45 or thrust member 15 which may be in the form of a bar of some length. This member 15 has opposed to it a thrusting screw 16 which is screw-threaded into the block 4a and which is adapted, in response to rotation, to exert a thrust 50 against the member 15, whereby a further compression results independent of and additional to the compression caused by the actuation of the normal locking means. It is highly important that the hair be firmly gripped and this 55

additional gripping means permits an exceedingly firm grip and is of course independent of any unintended loosening which may result from wear of the hinges or of the locking means or of the rubber lips 13, 13a. It will be understood that these rubber blocks may be formed as single integral pieces, including the lips 13, 13a, and that the abutment 15 may be integrally associated with one of these blocks, for example, by being molded therewith when the block is formed. If desired, the blocks 12, 12a, may be made readily removable from the upper blocks 4, 4a, or they may be cemented permanently thereto.

15 They are provided with opposed apertures or slots generally indicated as 17, through which pass cam or guide members 18, a pair of which project inwardly from the inner faces of each of the blocks 4, 4a. These members 18 have inclined 20 inner edges 18a which serve to gather the hair of the lock and thrust it into a more or less central position of the protector. It is preferable to wind a generally round lock about the below described curler and a concentration of the hair 25 in the protector is therefore desirable and is readily obtained by the camming action of the edges 18a of the members 18, as the protector members 1, 2, are moved into closing position.

We may employ any suitable heat insulation 30 means to protect the scalp from the application of heat to the hair above the protector. We may employ, for example, insulating pads 19 of felt or any other suitable fibrous material or of any material effective to limit or radically reduce 35 heat transmission. It will be understood, of course, that the same result might be obtained by the employment of air spaces.

Assuming that the protector is locked in position as above described and the necessary compression applied to the roots of the hair, the lock 40 of hair is then wound on any suitable curler. We illustrate, for example, a curler spool 20 with a pin at one end having a head shaped identically with the head of the screw 16. We may then employ any suitable key 30 having a socket which 45 will take the head of either of these two members. It will be observed that at one end of the curler 20 is a squared abutment member 21 which is connected with the curler 20 by any suitable 50 overrunning clutch, the details of which form no part of the present invention, whereby the curler body may be turned in one direction in relation to the squared member 21, but not in the other. 55 22 is any suitable initial clamping member which conforms in shape to the curler 20 and which is hinged thereto at one end as at 23. In order to mount the curler on the protector we provide a pair of ears at one end of the protector indicated at 24. This is in the form of a single piece at 60 the hinge end of the device. This member 24 has opposed upstanding ears 25 separated by a space 26 of the right separation to receive the squared member 21 of the curler. At the opposite end of each of the individual blocks 4, 4a 65 is an upstanding ear 27. When the device is in closed position these ears are separated a sufficient distance to permit the passage therethrough of the key receiving projection 28 of the curler. It will be understood that the curler, upon being applied to a lock of hair, is rotated until the lock is entirely wound thereabout and this rotation is continued until the hair is wound as tightly as is desired. The lock of hair cannot slip in relation to the protector and it is simply 70 wound in to the desired tightness until the curler 75

and the hair are in the position in which they are shown in Figure 6.

It will be realized that whereas we have described and shown a practical and operative device, nevertheless many changes may be made in the size, shape, number and disposition of parts without departing from the spirit of our invention. We wish our drawings and description, therefore, to be taken as in a broad sense illustrative and diagrammatic rather than as limiting us to our particular showing. In particular, it will be understood that a wide variety of materials may be employed, for gripping the hair and for protecting the scalp. Sponge rubber is a very efficient sealing means for protecting the scalp by preventing steam and heat from reaching it. Other compressible or flexible materials may be employed for gripping the hair and any suitable heat insulating means for protecting the scalp. The particular location of the abutment 8 for protecting a supplemental thrust against the hair may also be widely varied. In the place of the screw 16 we might use any suitable wedge or device for causing such a supplemental thrust. Furthermore, the faces of the rubber lips 13, 13a 25 may be corrugated as shown in Figures 5 and 6 to increase the gripping force of the protector. Whereas we have shown but a single such screw, two or more might be employed. Where we have shown such screw on one side only of the protector, it will be understood that they might be employed on opposite sides.

As an example of possible changes we illustrate in Figure 8 a variant form of applying pressure to the bar 15 in the form of a wedge member 31 and pivoted as at 32 within a socket or aperture 33. 34 is a rod pivoted to the member 2 as at 35. It includes a screwthreaded portion 36 which passes through a pivoted bearing 37. It may terminate in a terminal outside end at 40 38. It is shown in the drawings as knurled but it will be realized that it may be squared or hexed to receive the key 30 shown for example in Figure 3. The form of Figures 8 and 9 has the advantage of being located at or beyond the end 45 of the device so that it will not in any way interfere with the heating members 40 shown in Figure 10. These heating members 40, pivoted together as at 41, and provided with any suitable electric conductors 42 have internal resistance 50 elements not herein shown in detail. It will be understood that the heaters are in effect a spring clamp, any suitable yielding means being employed, not herein shown, for urging the members 40 into the position they are shown in Figure 10 about one of the curlers 20, and about the hair curled about such curler. Since a spring clip is employed it is important that no parts extend upwardly above the surface of the members 4, 4a, except at the very ends of the device 60 where mounting means for the curler 20 have to be provided in the form of the ears 25, and 27. It will be observed, as in Figure 2, that the locking means are entirely positioned along the end in such position as not in any way to interfere 65 with the application or removal of the heating members 40.

We illustrate in Figures 11 to 13 an improved type of curler. The body 50 is provided with a knurled portion 51 at its area of minimum diameter. It is also provided with knurled portions 52 at the ends thereof. The clamping arm 53 is recessed into the curler at its ends, as at 54, 55, it being pivoted in one of said recesses as at 56. The intermediate portion 57 surrounds and conforms 75

to the surface of the knurled portion 51 of the body 50. We illustrate a knurled turning member 58. It will be understood, of course, that it may be made to receive a key, to correspond to the showing of Figure 3. Whereas we have described the roughened portions 51, 52 as knurled, they may be roughened in any other suitable way.

A particularly important feature about the present device, is the efficiency of the locking means. It will be observed, as in Figure 1, that the link 8 is pivoted to the lever 9 a substantial distance from its pivot point. Thereby, when the link and lever are moved into locking position a very substantial tension is put upon the link 8 and the blocks 4 and 4a are drawn very firmly together compressing the yielding members 13 and 13a between them.

A further feature of our device consists in the fact that the members 19 may be formed somewhat cupped, as shown in Figures 6 and 10, to conform generally to the head of the subject.

We claim:

1. A protector for hair treatments, which includes two blocks, hinged together at one end, and locking means associated with the opposite ends of the blocks for locking said blocks together, including a locking lever pivoted to one of said blocks, a link pivoted to said locking lever at a point spaced from said lever point and extending across the end of the other block, and a locking connection between said link and said other block.

2. A protector for hair treatments, which includes two blocks, hinged together at one end, and locking means associated with the opposite ends of the blocks for locking said blocks together, including a locking lever pivoted to one of said blocks, a link pivoted to said locking lever at a point spaced from said lever point and extending across the end of the other block, and a locking connection between said link and said other block, and a manually engageable projection associated with said locking lever.

3. A protector for hair treatments, which includes two blocks, said blocks being pivoted to each other at one end, and being provided with opposed hair clamping members along their abutting side edges, and locking means for the opposite end of said blocks, said locking means, when in locking position, being located along the ends of said blocks, whereby the side edges of the blocks are left free, said locking means including a lever pivoted to one of said blocks, a link pivoted to said lever a substantial distance from the axis of rotation of the lever, and an abutment upon the opposite block, adapted to receive said link.

4. A protector for hair treatments, which includes two blocks, said blocks being pivoted to each other at one end, and being provided with opposed hair clamping members along their abutting side edges, and locking means for the opposite end of said blocks, said locking means, when in locking position, being located along the ends of said blocks, whereby the side edges of the blocks are left free, said locking means including a lever pivoted to one of said blocks, a link pivoted to said lever a substantial distance from the axis of rotation of the lever, and an abutment upon the opposite block, adapted to receive said link, the pivotal connection between the link and the lever being, when the parts are in locking position, over dead center in relation to the pivot point of the lever, whereby the compression of the parts tends to hold the lever in locked position.

5. A protector for hair treatments, which includes two blocks, said blocks being pivoted to each other at one end, and being provided with opposed hair clamping members along their abutting side edges, and locking means for the opposite end of said blocks, said locking means, when in locking position, being located along the ends of said blocks, whereby the side edges of the blocks are left free, said locking means including a lever pivoted to one of said blocks, a link pivoted to said lever a substantial distance from the axis of rotation of the lever, and an abutment upon the opposite block, adapted to receive said link, said lever, when in locking position, extending along one end of the protector, and extending slightly beyond one outside edge of the protector.

6. A protector for hair treatments, which includes two blocks, said blocks being pivoted to each other at one end, and being provided with opposed hair clamping members along their abutting side edges, and locking means for the opposite end of said blocks, said locking means, when in locking position, being located along the ends of said blocks, whereby the side edges of the blocks are left free, said locking means including a lever pivoted to one of said blocks, a link pivoted to said lever a substantial distance from the axis of rotation of the lever, and an abutment upon the opposite block, adapted to receive said link, said lever, when in locking position, extending along one end of the protector, and extending slightly beyond one outside edge of the protector, the length of said lever being substantially less than the total width of the protector.

PIERRE ALBERT. 55
GUSTAF WICKSTROM.
